UNITED STATES PATENT OFFICE

HOWARD C. MEAD, OF ANDERSON, INDIANA, ASSIGNOR TO GUIDE LAMP CORPORATION,
OF ANDERSON, INDIANA, A CORPORATION OF DELAWARE

TAIL LAMP

Application filed July 29, 1932. Serial No. 625,775.

This invention has to do with rear lamps for automobiles such as are commonly mounted on the rear fenders. The invention consists in designing the lamp so that it may be cheaply made out of sheet metal and easily assembled.

In the drawings:

Figure 1 is a vertical section through the improved lamp.

10 Figure 2 is an exploded view of the parts of the lamp assembly.

Figure 3 shows a modified assembly which may be employed.

15 Figure 4 is a section through a slightly modified design of lamp.

Figure 5 is a view of the back of the lamp housing of the construction shown in Figure 4.

10 indicates a cup-shaped stamping drawn 20 out of flat sheet metal having one end 12 expanded to form a lamp housing. The closed end of the stamping is indicated at 14. The member 10 may be apertured as shown at 16 to receive the usual glass 18 through 25 which light is projected on the license plate. Over the end 12 of the stamping is secured a cover glass 20. The cover glass may be secured in position by lens ring 22 having an inturned flange 24 provided with an aperture 26 to receive tongue 28 extending upwardly from an inturned flange formed on the expanded portion of the stamping 10. To the lower end of the lens ring 22 is secured stamping 30 having a threaded aperture 35 within which is received the screw 32 passing through a hole in the stamping 10.

The closed end 14 of the stamping 10 is preferably provided with an angled circular boss 34 having a central aperture.

40 Lamp socket 36 is secured to the aperture by means of an integral rivet 38 as shown in Figure 1.

The rear portion 40 of the lamp assembly 45 likewise preferably consists of a cup-shaped stamping drawn out of flat sheet metal having an expanded end 42 closed by means of plate 44 held in place by spinning the edge of the stamping over it. The closed end of the stamping is indicated by character 44'. 50 If desired members 10 and 40 may be made

of severed pieces or of one piece with a welded longitudinal seam but the described construction while more difficult to form is cheaper and much more satisfactory. Within the closed end of the stamping 40 is secured a stiffening plate 46, likewise apertured.

I have shown at 48 a license plate holder having an extension 50 apertured in alignment with the apertures in the closed ends 60 of the stampings 10 and 40, and in the stiffening plate 46. The extension 50 preferably conforms somewhat in shape to the ends of the stampings and may be provided with diverging flanges 52 bearing against the 65 sides of the stamping 40.

The described parts may be assembled as shown in Figure 1 with the license plate holder 48 arranged between the stampings. The parts are secured together by screws or 70 other fastening means 54 passing through the parts 14, 50, 44' and 46, and preferably threaded in bosses formed in the latter. With this arrangement, the fastening means is concealed within the tubular stampings. 75 The conductors 56 supplying current to the lamp 58 mounted in socket 36 extend through the aligned apertures previously referred to and are concealed from view within the tubular stamping 40. 80

The described construction will serve for the left rear fender lamp, the lamp being secured in place by suitable fastening bolts passing through the fender and the apertures 58 in the plate 44. 85

For the right rear fender, the plate 48 may be omitted, the parts then being assembled as shown in Figure 3. With this arrangement, by properly finishing the stampings, the appearance of an integral structure 90 may be obtained.

The socket 36 is preferably mounted on an upturned boss 34 as described, so that the bulb may be very close to the license plate window 18, insuring better illumination. 95

By providing two rear lamp assemblies, one with a license plate holder and one without, and both made up of identical elements, standardization of parts is insured and the cost of manufacture is reduced. The slight 100

difference in extent of projection of the two rear lamps owing to the omission of the license plate holder 48 from one of them will be found to be so slight as not to be noticeable.

In the form shown in Figures 4 and 5, 60 indicates the integral cup-shaped lamp housing, 62 the cup-shaped support, and 64 the license plate holder interposed between 10 the lamp housing and support. The chief difference in construction between this form and that previously described lies in the fact that the bulbs 66 and 68 are mounted in supports 70 and 72, respectively, pressed 15 out of the license plate holder 64. Another difference consists in the fact that the closed end of the stamping 60 is provided with a depression 74 exactly fitting the depending portion of the license plate holder, thereby 20 holding it against movement. The end of the lamp housing is likewise provided with a central aperture 76, shaped to permit passage of the supports 70 and 72 bent up from the license plate holder.

25 The bulbs 66 and 68 may be supported in any suitable manner in the supports 70 and 72. The leads from the bulbs are shown passing through rubber grommet 78 fitted into an aperture in the reinforcing plate 80. 30 The described parts may be held assembled by suitable fastening means such as screws 82 as in the case of the form first described.

I claim:

35 1. In a lamp for automobiles and the like, the combination of a pair of tubular stampings each having one end expanded, the opposite ends of the stampings being alined, means housed within said stampings for securing said ends together, a lamp socket mounted in one of said stampings, a lamp in the socket, a cover glass over the expanded end of said stamping, and a conductor connected to the socket and concealed within the stampings.

45 2. In a lamp for automobiles and the like, the combination of a pair of tubular stampings, each having one end thereof expanded, the opposite ends of the stampings being closed and arranged in alinement, a stiffening plate secured in the closed end of one 50 of said stampings, securing means passing through said closed ends and the stiffening plate, a lamp socket mounted in one of said stampings, a lamp in the socket, a cover glass over the expanded end of said stamping, and a conductor housed within the other stamping and connected to the socket.

60 3. In a lamp for automobiles and the like, the combination of a pair of tubular stampings, each having one end thereof expanded, the opposite ends of the stampings being closed and arranged in alinement, a stiffening plate secured in the closed end of one 65 of said stampings, securing means passing through said closed ends and the stiffening

plate, a lamp socket mounted in one of said stampings, a lamp in the socket, a cover glass over the expanded end of said stamping, a conductor housed within the other stamping and connected to the socket, and a 70 plate of stiff material secured in the expanded end of said last-named stamping and adapted to receive securing means fastening the lamp to a suitable support.

4. In a lamp for automobiles and the 75 like, the combination of an integral tubular stamping having one end expanded to form the body of the lamp, a cover glass over said end, the opposite end of said stamping being provided with an integral closure, a second tubular stamping having an expanded 80 end, a cover secured over said end, the opposite end of the stamping having a stiffening plate secured therein, and fastening means connecting the closed end 85 of the first named stamping and the stiffening plate and concealed within the stampings.

5. In a lamp for automobiles and the like, the combination of an integral tubular 90 stamping having one end expanded to form the body of the lamp, a cover glass over said end, the opposite end of said stamping being provided with an integral closure, a second tubular stamping having an expanded 95 end, the opposite end of the stamping having a stiffening plate secured therein, said end being alined with the closed end of the first-named stamping, a license supporting plate between said alined ends, means 100 housed within said stampings and passing through said closure, stiffening plate and supporting plate securing said stampings together, a lamp in said first named stamping, and a conductor leading therefrom and 105 housed within said stampings.

In testimony whereof I affix my signature.

HOWARD C. MEAD.
